Raymond A. Pullon, Milford, Conn., assignor to
The A. C. Gilbert Company, New Haven, Conn.,
a corporation of Maryland

Application December 29, 1950, Serial No. 13,619

Term of patent 14 years

(Cl. D26—13)

To all whom it may concern:

Be it known that I, Raymond A. Pullon, a citizen of the United States, residing at Milford, in the county of New Haven and State of Connecticut, have invented a new, original, and ornamental Design for a Toy Train Controller or the like, of which the following is a specification, reference being had to the accompanying drawings, forming part hereof.

Fig. 1 is a perspective view and Figs. 2, 3 and 4 are respectively plan, side and front views of a toy train controller or the like showing my new design.

I claim:

The ornamental design for a toy train controller or the like, substantially as shown.

RAYMOND A. PULLON.
